STRAND-ADVANCING APPARATUS

Paul R. Powell, Baltimore, Md., assignor to Western Electric Company, Incorporated, New York, N. Y., a corporation of New York

Application April 22, 1950; Serial No. 157,554

16 Claims. (Cl. 203—227)

1

This invention relates to strand-advancing apparatus, and more particularly to tractor-type capstans for advancing strands, cables and the like.

An object of the invention is to provide new and improved strand-advancing apparatus.

Another object of the invention is to provide new and improved tractor-type capstans for advancing strands, cables and the like through and from machines in which they are being processed.

A further object of the invention is to provide a tractor-type capstan suitable to advance cables of different sizes.

A strand advancing apparatus illustrating certain features of the invention, may include a plurality of endless belts having gripping shoes mounted on the belts for advancing a strand through the apparatus, a plurality of guideways for guiding the belts along predetermined paths so that portions thereof face toward a common axis, a system of pivotally mounted members for movably supporting the guideways so that portions of the belts are parallel to the axis, and means for selectively moving the members to adjust the space between the belts to suit the size of the strand to be advanced by the belts.

Other objects and advantages of the invention will appear from the following detailed description of an apparatus forming a specific embodiment thereof, when read in conjunction with the appended drawings, in which:

Fig. 1 is a front elevation of a tractor-type capstan embodying certain features of the invention having portions thereof broken away;

Fig. 2 is a horizontal section taken along line 2—2 of Fig. 1;

Fig. 3 is a rear elevation of the apparatus shown in Fig. 1 having portions thereof broken away;

Fig. 4 is an enlarged, fragmentary, vertical section taken along line 4—4 of Fig. 1;

Fig. 5 is an enlarged, perspective view of one of the gripping shoes attached to the endless belts shown in Fig. 4.

Fig. 6 is a plan view of a portion of the apparatus shown in Fig. 1, and

Fig. 7 is a fragmentary front elevation of the apparatus shown in Fig. 6.

Referring now in detail to the drawings and more particularly to Fig. 1, there is shown therein a tractor-type capstan including a pair of endless chain belts 10 and 11 arranged to travel in the same plane in juxtaposed positions so spaced that the adjacent portions of the belts may engage a cable core 13 positioned therebetween. The cable core includes a plurality of conduc-

2

tors having several layers of impregnated paper spirally wound therearound, and is advanced by the capstan (Fig. 1) from a reel or a cable-forming mechanism (not shown).

5 The chain belts 10 and 11 (Figs. 4 and 5) are identical in construction and operation, and include roller chains 15 and 16 bound together at each link thereof by transverse crossbars 17—17. The transverse bars 17—17 are provided with 10 channel-shaped ends 18—18 for detachably clamping flexible gripping shoes 20—20 to the belts for exerting a frictional gripping action on the core 13. The gripping shoes preferably should be made of a flexible and elastic material which 15 is substantially non-compressible, such as rubber, compounds containing natural rubber, or rubber-like compounds such as polymerized chloroprene (neoprene). A slot 23 is provided in each end of the shoes into which fit ribs 25—25 provided in the corresponding ends of the bars 17—17. The ribs 25—25 of the crossbars 17—17 key the gripping shoes 20—20 to these bars and secure them to the chains 15 and 16. The gripping shoes 20—20 are inserted in the bars 17—17 by bending the shoes so that the ends thereof fit between the edges of the channels 18—18 and then releasing the shoes so that they snap into their normal shape as shown in Fig. 4. Each of the gripping shoes is provided with a recess 27 on the underside thereof and with concave 20 grooves 28—28 on the opposite side thereof, the radius of which is slightly greater than the radius of the maximum size of cable core to be engaged by belts 10 and 11. This arrangement of the 25 groove 28 and the recess 27 in the shoes produces 30 opposed leg portions 26—26 having arcuate gripping surfaces and connected together with a thin, bendable section 29 (Figs. 4 and 5).

The endless chain 15 (Figs. 2 and 4) of the belt 10 travels around sprockets 30 and 31, and the chain 16 travels around sprockets 32 and 33. The sprockets 30 and 32 are secured on a bushing 34 so that their teeth are aligned transversely with each other, and spaced apart a distance 40 equal to the spacing of the chains 15 and 16 on the crossbars 17—17. The assembly of the sprockets 30 and 32 and the bushing 34 is mounted rotatably on a post 35 secured near the left-hand end of an I-shaped support 36. The sprockets 31 and 33 are assembled in a similar manner on a bushing 37 rotatably mounted on a post 38 secured near the right-hand end of the support 36 so as to be coextensive with the post 35. The support 36 (Fig. 4) is of such width that 45 the elongated legs of the endless belt 10 ride on 55

backing plates 40 and 41 of the support. The plate 40 of the support 36 is positioned adjacent to the cable core 13 and serves to hold the gripping shoes 20-20 of the belt 10 in positive engagement with the surface of the cable core 13.

The chain 16 (Figs. 1 and 2) of the belt 11 travels around sprockets 44 and 45 mounted on bushings 46 and 47, respectively, which in turn, are mounted rotatably on posts 50 and 51, respectively. The posts 50 and 51 are mounted co-extensively on an I-shaped support 52, which is identical with the support 36. The posts 50 and 51 are positioned apart on the support 52 a distance equal to the distance between the posts 35 and 38. The chain 15 of the belt 10 travels around sprockets like the sprockets 44 and 45 which are secured to the bushings 46 and 47 in the same manner as that in which the sprockets 39 and 31 are secured to the bushings 34 and 37, respectively.

The support 52 is designed so that the chains 15 and 16 of the belt 11 ride on backing plates 53 and 54 (Fig. 1) of the support. The plate 53 of the support 52 is positioned adjacent to the cable core 13 and serves to hold the gripping shoes 20-20 of the belt 11 in positive engagement with the cable core 13. The backing plates 40 and 53 of the supports 36 and 52, respectively, have their end portions 55-55 and 56-56, respectively, arranged to slope away from the cable core 13 to cause the shoes to engage the cable core at the entrance end of the capstan and to leave the cable core at the opposite end of the capstan without effecting any rotation of the shoes while their grooves 28-28 grip the cable core. This feature of the supports 36 and 52 prevents the gripping shoes from moving along the core 13 after they engage the core thereby preventing the gripping shoes from tearing the paper covering of the core.

The support 36 (Figs. 1, 2 and 3) is mounted pivotally on posts 57-57 secured in the upper right-hand corner portions of a pair of segmental gears 58-58, as viewed in Fig. 3. The gears 58-58 are mounted pivotally on posts 60-60 rigidly secured in predetermined spaced relationship to a plate 61 secured to a frame 64 designed to support the belts 10 and 11 and other moving parts of the capstan. The posts 60-60 are mounted on the plate 61 in a plane which is parallel to the central axis of the belt 10. A link 65 holds the gears 58-58 parallel, whereby the gears 58-58 position the support 36 so that the backing plate 41 of the support is always horizontal, as viewed in Fig. 1. Consequently, the backing plate 41 holds the portion of the belt 10 thereon horizontal, irrespective of the positions of the gears 58-58.

The support 52, which carries the belt 11, is mounted in a similar manner on posts 63-63 secured in the right-hand corner portions of segmental gears 70-70 (Fig. 3) mounted pivotally on posts 71-71 connected rigidly to the plate 61. The posts 71-71 are mounted in a plane which is parallel to the central axis of the belt 11. The free ends of the gears 58-58 and 70-70 are provided with conventional gear teeth which intermesh in such a manner that the gears 70-70 are maintained parallel. By locking the gears 58-58 and 70-70 together in this manner, the support 52 is so held that the backing plate 54 thereon is parallel to the backing plate 41 of the upper support 36. Consequently, the portions of the belts 10 and 11 riding on the backing plates 41 and 54 maintain the cable core 13 parallel

thereto. This arrangement of the supports 36 and 52 on the gears 58-58 and 70-70 maintains the juxtaposed portions of the belts 10 and 11 in strict parallelism. The weight of the belt 10 tends to turn the gears 58-58 about the posts 60-60 in a clockwise direction as viewed in Fig. 3 and the weight of the belt 11 tends to turn its respective gears 70-70 about the posts 71-71 in a clockwise direction. As a result, the free ends of the gears 58-58 and 70-70 tend to move in opposite directions, but since the weights of the belts are substantially equal, the force exerted on the gears is neutralized and the belts will remain in any set position of the gears 58-58 and 70-70.

To adjust the transverse spacing between the belts 10 and 11 to suit various sizes of cable cores or cable to be advanced by the belts, a crank 73 (Fig. 3) is secured to the gear 58 at the right of the post 60, as viewed in Fig. 3, so that it pivots

about the post 60. A nut 74 (Fig. 2) is secured to the end of the crank and the adjacent side of the gear 58 so that it is free to swivel about the end of the crank 73. The nut 74 is designed to receive the threaded end of a shaft 75 mounted rotatably in a thrust bearing 76 secured on the frame 64 and a handwheel 78 is secured to the shaft. The handwheel may be actuated selectively to pivot the crank 73 to move the juxtaposed portions of the belts closer together or farther apart, movement of the gear 58 imparting a corresponding movement to the other gear 58 and equal and opposite movement to the gears 70-70.

A sprocket 80 (Fig. 1), keyed to the bushing 34 between the sprockets 30 and 32 is driven by a drive sprocket 81 through a chain 82. The drive sprocket 81 is keyed to a shaft 83 suitably journaled in the plate 61. A spring-biased rocker arm 86 pivotally mounted on the shaft 83 urges an idler sprocket 87, secured on one end thereof, into engagement with the chain 82, to keep slack out of the chain. A sprocket 90, keyed to the bushing 46, between the sprockets driving the chains 15 and 16 of the belt 11, is driven by a sprocket 91 through a chain 92. The sprocket 91 is keyed to a shaft 95 suitably journaled in the plate 61 and transversely aligned with the shaft 83. A spring-biased rocker arm 96 pivotally mounted on the shaft 95 urges an idler sprocket 97 mounted on one end thereof into engagement with the chain 92 to take slack out of the chain. The free ends of the rocker arms 86 and 96 are connected to a tension spring 100.

A sprocket 103 (Figs. 2 and 3) keyed to the end of the shaft 83 and a sprocket 104 identical therewith keyed to the shaft 95 are driven in opposite directions by a sprocket 105 through a chain 106 which passes around the sprockets in the manner shown in Fig. 3. The sprocket 105 is keyed to the output shaft of a gear reducer 107 directly coupled to a motor 108. The motor 108 is arranged to drive the sprocket 105 in a counter-clockwise direction, as viewed in Fig. 3, to drive the belts 10 and 11 to advance the cable core 13 from right to left, as viewed in Fig. 1. An idler sprocket 110 mounted on the end of a pivotally mounted arm 111, biased in a clockwise direction, as viewed in Fig. 3, by a tension spring 112, keeps the chain 106 taut. This arrangement of the idler sprocket 110 permits the belts 10 and 11 to be moved toward or away from each other without having to change the length of the chain 106.

Guide plates 113-113 (Figs. 3 and 4) secured to the edges of the backing plates of the supports

36 and 52 keep the endless belts 10 and 11 on the backing plates 41 and 53 of the supports 36 and 52, respectively. Guide channels 114-114 secured on the edges of the backing plates 40 and 54 include longitudinal shoulders 115-115 which engage the crossbars 17-17 of the belts and keep the chains 15 and 16 thereof in engagement with the bracket plates 40 and 54. The I-shaped supports 36 and 52 with their associated guide plates 113-113 and guide channels 114-114 together 10 constitute guideways for the endless belts 10 and 11.

A sprocket 116 (Figs. 2 and 3) keyed for rotation with the shaft 83 drives a sprocket 117 by means of a chain 118. The sprocket 117 is connected to the driving side of a friction clutch 119 (Fig. 6) which has its driven portion keyed to a shaft 120 suitably journaled on the upper right-hand portion of the frame 64, as viewed in Fig. 3. The clutch 119 is operable by a fork lever 121 pivotally mounted on the frame 64. The free end of the fork lever 121 is connected to a rod 123 slidably mounted on the frame and with its free end positioned near the front of the capstan so that the clutch 119 may be actuated from the front side of the capstan. A sprocket 124 keyed to the shaft 120 (Figs. 2 and 3) is connected by a chain 125 to a sprocket 126 keyed to a shaft 127 suitably journaled in the frame 64.

The shafts 120 and 127 extend beyond the frame 64 so that their free ends extend slightly beyond the front side of the frame. A wire rope capstan 130 (Figs. 6 and 7) is keyed to the end of the shaft 120 and a wire rope takeup drum 131 is keyed to the front end of the shaft 127. The capstan 130 and the takeup drum 131 are used when it is necessary to start a cable core between the endless belts 10 and 11. It is necessary to position the cable core 13 between the belts 10 and 11 so that the entire length of the juxtaposed portions of the belts can grip the cable core in order to prevent possible injury to the gripping shoes and the core.

To start the cable core 13 through the apparatus, a suitable length of wire rope 133 is withdrawn from the takeup drum 131 and the end thereof is connected to a hook 134 secured to the leading end of the cable core 13. The wire rope 133 extends from the hook 134 past a guide roller 135 mounted on a spring-biased arm 136 pivotally mounted on a bracket 137. The rope 133 extends outwardly from the roller 135 some distance to a sheave 138 (Fig. 7) mounted on a column 139 rigidly secured to the floor. The rope 133 passes around the sheave 138, reversing its direction, and passes around a guide roller 140 positioned on the frame 64 to the capstan 130. It passes around the capstan 130 several times, and passes downwardly to the takeup drum 131. When the rope is threaded through the apparatus in this manner, the clutch 119 is actuated manually by the rod 123. Actuation of the clutch causes the sprocket 117 to drive the shaft 120 and the capstan 130 secured on the end of the shaft 120. The shaft 120 also drives the shaft 127 through the sprockets 124 and 126 and the chain 125, thereby rotating the takeup drum 131. When the capstan 130 and the takeup drum 131 are driven in this manner, the wire rope 133 is drawn to the left and threads the cable core 13 between the endless belts 10 and 11. When the leading end of the cable core 13 emerges from the frame 64, it actuates a latch 141 to release the roller 135 and the arm 136, which then are moved to their broken-line positions as viewed in Fig. 6.

so that they clear the cable core as it passes from the belts. At the entrance end of the frame 64, there is provided guide rollers 143-143 mounted on a threaded shaft 145 provided with a hand-wheel 146 for moving the rollers together and apart. These rollers serve to center the cable core 13 between the belts and prevent excessive lateral movement of the cable as it enters the capstan. A guide bushing 150 (Fig. 1) secured in the exit end of the frame 64 guides the cable core 13 as it leaves the belts.

Operation

The guide rollers 143-143 are moved apart to suit the size of the cable core to be advanced by the capstan. The wire rope 133 is threaded between the belts 10 and 11 and is connected to the hook 134 provided on the leading end of the cable core 13 and the motor 108 is energized to drive the belts 10 and 11. The handwheel 78 is turned in a direction which will pivot the gears 58-58 about the posts 60-60 in a counterclockwise direction as viewed in Fig. 3. This movement of the gears 58-58 imparts a corresponding movement to the gears 70-70 about their respective posts 71-71 in a clockwise direction. When the gears 58-58 and 70-70 move in this manner, the belts 10 and 11 move away from each other. The handwheel is turned until the space between the juxtaposed portions of the belts is greater than the diameter of the cable core 13.

After the belts 10 and 11 are adjusted in this manner, the clutch 119 is actuated to cause the capstan 130 to pull the wire rope 133 to the left, as viewed in Fig. 6, and thereby thread the end of the cable core between the juxtaposed portions of the belts 10 and 11.

When the leading end of the core emerges from the bushing 150, it turns the latch 141 to allow the spring-biased guide roller 135 to move out of the path of travel of the core. When the core reaches this point the clutch lever 121 is actuated manually to disconnect the sprocket 117 from the shaft 120, whereupon the capstan 130 and the takeup drum 131 are rendered inoperative. The wire rope 133 is removed from the hook 134, and is coiled up on the takeup drum 131 by again actuating the clutch until the end of the wire rope 133 reaches the capstan 130.

The motor 108 is deenergized to stop the belts, and the handwheel 78 is actuated to move the belts 10 and 11 toward each other until the thin center portion 29 of the gripping shoes 20-20 riding on the backing plates 40 and 53 exerts a pressure on the cable core sufficient to bend the gripping shoes and cause the edge portions of their concave surfaces 28-28 to pivot inwardly so that the entire concave surface of each gripping shoe engages the cable core. Since the center portion 29 of the shoes 20-20 is not backed up by the transverse bars because of the recesses 27-27, the leg portions 26-26 of the gripping shoes exert a maximum gripping force on the core 13 at four diametrically opposed arcs of contact about the periphery of the core as indicated by the arcs designated A, B, C and D in Fig. 4. Thus, the gripping shoes apply equal pressure to the core at opposite points around its periphery, thereby preventing the belts 10 and 11 from crushing or damaging the core 13.

This construction of each gripping shoe produces, in effect, a pair of opposed jaws pivotable centrally thereof and having arcuate gripping surfaces, and a lever connecting the jaws together adjacent to their pivot point. When the

belts 10 and 11 are adjusted as described, the core pushes the lever inwardly and thereby pivots the jaws toward each other so that the arcuate gripping surfaces engage the core.

After the belts 10 and 11 have been adjusted in this manner, the motor 108 again is energized to drive the belts through the sprockets 103 and 104 and the chain 106, as seen in Fig. 3. When the belts are driven in this manner they advance the cable core 13 through the capstan from right to left as seen in Fig. 1. The inclined end portions 55 and 56 of the supports 36 and 52, respectively, cause the gripping shoes 20-20 on the belts 10 and 11 to travel in gradually sloping paths as they approach and as they recede from the core 13, thereby preventing relative longitudinal movement between adjacent shoes on the belts in gripping and releasing the cable core.

The gripping shoes 20-20 are designed so that the radius of the grooves 28-28 is slightly greater than the radius of the largest cable core to be advanced by the endless belts 10 and 11. When the largest cable cores are advanced by the belts, only a minimum deformation of the gripping shoes is required to cause the belts to grip the cable core with sufficient force to advance it from left to right, as viewed in Fig. 3. When cable cores having a diameter slightly less than that of the largest size core are to be advanced by the belts, the belts are moved toward each other so that the gripping shoes are deformed to a greater degree and cause the entire curved surface thereof to contact the core. When it is desirable to advance a cable core having a diameter beyond the range that the gripping shoes can be deformed to grip the cable core, the gripping shoes 20-20 are replaced by other gripping shoes provided with a concave gripping surface having a radius designed to suit the range of core sizes in which that core falls. The gripping shoes 20-20 may be readily removed from their respective crossbars 17-17 when necessary without having to remove the endless belts 10 and 11 from the respective sprockets.

The supports 36 and 52 are mounted pivotally on the segmental gears 58-58 and 70-70, which are tied together by the connecting link 65 so that their respective weights are balanced against each other, whereby the belts remain in any set position. When the belts 10 and 11 are adjusted to advance the cable core, the pressure of the gripping shoes 20-20 caused by the belt 10 tends to turn the gears 58-58 about the posts 60-60 in a counter-clockwise direction as viewed in Fig. 3. At the same time the pressure of the gripping shoes of the belt 11 tends to move the belt 11 away from the cable core and thereby turn the gears 70-70 about their respective posts 71-71 in a clockwise direction. Since the gears 58-58 and 70-70 are intermeshed, the tendency of each belt to move away from the cable core is counteracted by an equal opposite force existing in the other belt which tends to hold it against the cable core. Therefore, when the belts are properly adjusted, the traction that the gripping members exert on the cable core does not cause the belts to separate and relax their grip on the cable. This arrangement of the supports 36 and 52 and the gears 58-58 and 70-70 provides a very efficient and simple mechanism for adjusting the space between the belts to suit the size of the cable core to be advanced thereby, and maintains an accurate adjustment of the belts throughout long periods of operation.

It is to be understood that the capstan also

may be used in conjunction with cable-making apparatus for drawing a finished cable, such as a lead-sheathed cable, from various cable-forming mechanisms and delivering it to a takeup reel.

5 It will be obvious, of course, that tractor-type capstans embodying features of this invention are capable of numerous other uses.

While the above-described capstan is particularly well adapted for advancing cable cores through or from apparatus in which the cable is being processed, it may be readily adapted for advancing various types of elongated articles, such as wire rope, stranded cables, lead-sheathed cables, and the like without departing from the 15 spirit and scope of the invention.

It is to be understood that the endless belts 10-10 also may be provided with gripping members designed to act as dies for forming cables and tubular articles into desired shapes. The 20 apparatus is readily adaptable for these and other operations relating to elongated articles by the mechanism provided for adjusting the spacing between the belts to suit the size of the article positioned between mutually-facing portions of 25 the belts.

What is claimed is:

1. A strand-advancing apparatus, which comprises a plurality of endless belts, a plurality of guideways for guiding the belts along predetermined paths, a plurality of gripping shoes secured on the endless belts for engaging a strand to be advanced through the apparatus, a system of interconnected pivotally mounted members for supporting the guideways so that portions of the 30 belts travelling thereon face toward a common axis and are parallel to said axis, said members being so designed that movement of any one of them imparts equal and opposite movement to the guideways with respect to said axis, and 35 means for selectively moving the members to adjust the space between the belts to suit the size of the strand to be advanced by the belts.

2. A strand-advancing apparatus, which comprises a plurality of endless belts, a plurality of guideways for guiding the belts along predetermined paths, one for each belt, a plurality of pairs of spaced pivotally mounted levers for movably supporting the guideways, one pair of levers for each guideway, said guideways being arranged 45 on the levers so that a portion of their respective 50 belt faces toward a common longitudinal axis, a link connecting the pivotally mounted levers of one of the belts together so that a portion of the belt supported thereby is parallel to said 55 common axis, means for connecting free ends of all the levers together in such a position that 60 portions of the belts supported by the other pairs of levers are parallel to the longitudinal axis, a plurality of gripping shoes secured on the 65 endless belts for engaging a strand to be advanced along the common axis, said pivotally mounted levers being so connected that movement of any 70 one of the levers imparts equal movement toward or away from the common axis, and means for 75 selectively moving one of the levers to adjust the space between the belts and the common axis to suit the size of a cable to be advanced by the belts.

3. A strand-advancing apparatus, which comprises a pair of elongated members having opposed guideways, sprockets mounted on opposite ends of each of the guideways, a pair of endless chain belts arranged to travel on the guideways and around the associated sprockets thereof, one belt for each guideway, a pair of pivotally

mounted levers for movably supporting one of the guideways, a second pair of pivotally mounted levers for movably supporting the other guideway in such a position that the belts travel in the same plane and are disposed in spaced relationship, said levers being connected to maintain the opposed portions of the belts parallel and so that movement of any one of the levers imparts equal and opposite transverse movement to the guideways, a plurality of gripping shoes secured on the belts for engaging a strand to be advanced by the opposed portions of the belts, and means for selectively moving the levers to adjust the space between the opposed portions of the belts to suit the size of the strand to be advanced by the belts.

4. A capstan for advancing cables longitudinally of their length, which comprises a pair of endless belts, a plurality of cable gripping members secured to the moving belts for engaging a cable longitudinally positioned between the belts, a pair of I-shaped supports one for each belt, a pair of pivotally mounted levers for supporting one of the supports, a second pair of pivotally mounted levers for supporting the other support, a connecting link for maintaining the first-mentioned pair of levers in such a position that one portion of the belt supported thereby is maintained parallel to the longitudinal axis of a cable positioned between the mutually facing portions of the belts, means for connecting the free ends of the second pair of levers to the free ends of the first-mentioned levers so that the second pair of levers maintain a portion of the belt carried thereby parallel to the longitudinal axis of the cable, said levers being so linked together that movement of any one of its levers about its pivot point imparts equal and opposite transverse movement to the supports carrying the belts, and means for moving one of the pivotally mounted levers in either direction to adjust the space between the mutually-facing parallel portions of the belts to suit the size of the cable to be advanced thereby.

5. A capstan for advancing cables longitudinally of their length, which comprises a pair of endless belts, a plurality of resilient gripping shoes secured on the endless belts for engaging a cable to be advanced thereby, a pair of movable supports one for each belt, a system of levers connecting the supports together so that the endless belts travel in the same plane with their juxtaposed portions parallel to the longitudinal axis of the cable to be advanced by the belts, said system of levers being designed so that movement of any one of the levers imparts equal and opposite transverse movement to the supports, and means for selectively positioning the system of levers to adjust the space between the juxtaposed portions of the belts to suit the size of a cable to be advanced thereby.

6. A capstan for advancing cables, which comprises a pair of endless belts arranged to travel in the same plane and disposed in spaced relationship, a plurality of resilient gripping shoes secured on the endless belts for engaging a cable positioned longitudinally between the mutually-facing portions of the belts, a pair of spaced pivotally mounted levers for movably supporting one of the belts, a second pair of spaced pivotally mounted levers for movably supporting the other belt, a connecting link for holding the first-mentioned pair of levers in such a position that a portion of the belt supported thereby is parallel to the longitudinal axis of the cable to be advanced by the belts, said levers having gear teeth formed

on their free ends which intermesh with each other and hold the second pair of levers in such a position that a portion of the belt supported thereby is parallel to the longitudinal axis of the cable engaged by the belts, said pivotally mounted levers being arranged so that movement of any one of the levers imparts equal and opposite transverse movement to the belts, and means for selectively positioning the levers so as to adjust

10 the space between the mutually-facing parallel portions of the belts to suit the size of the cable being advanced by the belts.

7. A capstan for advancing cables, which comprises a pair of endless belts arranged to travel in the same plane and disposed in spaced relationship, a plurality of gripping members secured on the endless belts for engaging a cable longitudinally positioned between the mutually-facing portions of the belts, a pair of pivotally mounted levers for movably supporting one of the belts, a second pair of spaced pivotally mounted levers for movably supporting the other belt, a connecting link for holding the first-mentioned levers in such a position that one portion of the belt supported thereby is parallel to the longitudinal axis of the cable to be advanced by the belts, said levers having gear teeth formed on their adjacent ends which intermesh with each other so as to hold the second pair of levers in 20 such a position that a portion of the belt supported thereby is parallel to the longitudinal axis of the cable engaged by the belt, said pivotally mounted levers being arranged so that the weight of the belts tends to turn their respective levers 25 in opposite directions whereby movement of any one of the levers imparts equal and opposite transverse movement to the belts, a crank connected to one of the levers, and means for selectively actuating the crank so as to turn the lever 30 about its pivot point and thereby adjust the spacing between the mutually-facing parallel portions of the belt to suit the size of the cable being advanced thereby.

8. A strand-advancing apparatus, which comprises a pair of endless belts having strand-engaging surfaces thereon, a pair of guideways for guiding the belts along predetermined paths, a group of segmental gears mounted on fixed pivotal axes, pivotal mounting means positioned off-center on the gears connecting one of the belt-guideways to the gears to support the guideway thereby, a second group of segmental gears mounted on fixed pivotal axes and intermeshed with the gears of the first-mentioned group of 45 gears, pivotal mounting means connecting the other guideway to the gears of the second-mentioned group to support that guideway thereby, means linking together the gears supporting one of the guideways to orient all the gears in positions such that portions of the belts carried by the guideways face a common axis and are parallel to said axis, said pivotal mounting means being so connected to the gears that movement of any one of the gears imparts equal and opposite movements of the belts with respect to said common axis, and means for turning one of the gears about its pivot point to adjust the space between the belts to suit the size of the strand to be advanced by the apparatus.

9. A strand-gripper, which comprises a pair of legs having generally opposed gripping surfaces formed on the free end portions thereof, and a flexible web connecting the legs together at points thereon between the gripping surfaces and the opposite ends of the legs for pivoting the legs

11

to bring the gripping surfaces into engagement with a strand when the strand is pressed against the web.

10. A gripping shoe for strand-advancing apparatus, which comprises a flexible, but substantially non-compressible rubber block having thick opposed end portions provided with arcuate strand gripping surfaces, and a substantially thin web connecting the end portions for causing the end portions to turn inwardly and grip a strand when the strand is pressed against the web.

11. A gripping shoe for strand-advancing apparatus, which comprises a block of flexible, but substantially non-compressible material having a concave strand-gripping surface of a radius greater than that of the maximum size strand to be engaged by the shoe and a recess centrally positioned in the side thereof opposite the concave surface, said concave surface and recess forming a thin wall between the opposed outer portions of the shoe which bends when the shoe is engaged by a strand and pulls the outer portions of the concave surface inwardly into gripping engagement with the strand.

12. A strand-advancing apparatus, which comprises an endless belt movable along a predetermined path, a plurality of holders secured transversely on the belt, and a plurality of flexible strand-gripping shoes insertable in the holders for engaging a strand to be advanced by the apparatus, each of said gripping shoes having a concave strand-engaging surface of a radius greater than that of the maximum size strand to be engaged thereby and the central portion thereof being a flexible web yieldable toward the belt to cause the outer portions of the concave surface to tightly grip strands of different diameters.

13. A strand-advancing apparatus, which comprises an endless belt, a plurality of sockets secured transversely to the belt, and a plurality of resilient gripping shoes insertable in said sockets for engaging a strand to be advanced by the apparatus, said sockets having means thereon for keying the gripping shoes to the belt, each of said gripping shoes having a concave groove whose radius is greater than that of the maximum size strand to be advanced by the belt and a recess centrally positioned in the side thereof opposite to the groove, said recess permitting the gripping shoe to be bent toward the belt and cause the outer portions of the concave surface to grip tightly strands of any diameter between and including predetermined maximum and minimum values.

14. A strand-advancing apparatus, which comprises an endless belt having a portion thereof travelling parallel to a strand to be advanced by the apparatus, a holder secured on the belt and having channel-shaped ends provided with inwardly extending ribs and a flexible but substantially non-compressible rubber gripping shoe positioned in the holder and having slots in the sides thereof for receiving the ribs of the holder, said gripping shoe having a concave groove in its strand gripping surface whose radius is greater than that of the maximum size strand to be ad-

12

vanced by the apparatus and a recess centrally positioned in the opposite side thereof, said recess being provided in the gripping shoe so that it may be flexed sufficiently to be inserted into the channel-shaped ends of the holder and the shoe can be bent toward the belt, whereby opposed portions of the concave groove tightly grip strands of any diameter between and including predetermined maximum and minimum values.

10. 15. A capstan for advancing cables, which comprises a pair of endless belts, means for supporting the endless belts in the same plane and in spaced relationship, means for selectively positioning the supporting means so as to adjust the space between the mutually-facing parallel portions of the belt to suit the size of a cable to be advanced by the belts, and a plurality of flexible, but substantially non-compressible gripping shoes detachably secured on the endless belts for engaging the cable positioned between the mutually-facing portions of the belts, each of said gripping shoes having a concave cable engaging surface of a radius greater than that of the cable to be engaged thereby, and a recess centrally positioned in the side thereof opposite the groove, said recess being designed so that the shoes bend toward the belt when they engage the cable in such a manner that each pair of opposed shoes exerts maximum gripping force on the cable at four diametrically opposed arcs of contact about the periphery of the cable.

16. A capstan for advancing cables longitudinally of their length, which comprises a pair of endless belts, each of said belts includes a pair 35 of endless chains having bars secured transversely across the alternate lengths of the chains, means for movably positioning the belts so that they travel in the same plane with juxtaposed portions disposed in spaced relationship to suit 40 the size of a cable to be advanced by the apparatus, said bars having channel-shaped ends provided with an inwardly extending rib, and a flexible gripping shoe positioned in each transverse bar and having a slot in each end thereof 45 for receiving the corresponding ribs of its respective transverse bar, each of said gripping shoes having a concave groove in its cable gripping surface whose radius is greater than that of the maximum size cable to be advanced by the 50 apparatus and a recess positioned centrally in the opposite side thereof, said recess being provided in the gripping shoes so that they may be flexed sufficiently to be inserted into the channel-shaped ends of the bars and so that they will bend in the 55 center as they engage the cable and grip tightly cables of any diameter between and including predetermined maximum and minimum values at four diametrically opposed arcs of contact about the periphery of the cable.
